RUBBER ICE CREAM SHIPPER

Filed April 27, 1928

UNITED STATES PATENT OFFICE

SPENCER O. STAACE, OF EAU CLAIRE, WISCONSIN, ASSIGNOR OF ONE-HALF TO RALPH W. HUTCHENS, OF EAU CLAIRE, WISCONSIN

RUBBER ICE-CREAM SHIPPER

Application filed April 27, 1928. Serial No. 273,174.

My present invention relates to shipping containers, and more particularly to a shipping container for perishable goods such as ice-cream, milk and the like. Specifically, 5 this invention contemplates the provision of a shipper especially adapted for the shipping of cans of ice-cream.

Heretofore it has been customary to ship cans of ice-cream in either kegs of ice or cans 10 was lined bags filled with various kinds of heat insulating material, and at present there is quite a demand for an efficient shipper of the latter type which does not require the use of ice. However, due to the fact that the 15 canvas type of shipper is expensive and wears out quickly, it has not proven satisfactory enough to meet the demand. Also the canvas type of bag is in most cases unsanitary as well as cumbersome, and it does not present 20 an inviting appearance.

Therefore, I propose to provide an improved shipper of the type which does not require the use of ice for ice-cream containers and the like.

25 An object of the present invention is to provide a simple and inexpensive ice-cream shipper which is not only highly sanitary but in addition affords a neat and pleasing appearance.

30 Another object of my invention resides in the provision of a relatively rigid shipper made of a flexible material, whereby the wall of the shipper will adjust itself to conform to the shape of the ice-cream can disposed 35 therein, so that the shipper can receive the can even though there are slight bumps and irregularities in its surface.

Still another object of this invention is the provision of a shipping container for ice-cream shaped to conform with the can in 40 which the ice-cream is shipped.

A further object of my invention is to provide a rubber shipper adapted to receive bodily a container of ice-cream and to completely 45 protect and seal the ice-cream from the deleterious effects of the atmosphere surrounding the shipper.

A still further object of the invention resides in the provision of an improved shipper 50 per for cans of ice-cream and the like capable

of relatively rough handling and comprising a rubber container having spaced ribs formed on its inner surface for defining air pockets between the wall of the can and the shipper.

Still another and further object of this invention is to provide an inexpensive ice-cream shipper including two parts, namely a container proper and a top therefor, each of which parts comprises a single member of molded rubber.

In accordance with the features of the invention I provide an ice-cream shipper made substantially throughout of rubber including a container and a removable top connected thereto by a rubber strap serving as a handle, a handle having one end secured to the body or container of the shipper and having its other end arranged for cooperation with a buckle secured to the container opposite the first mentioned end of the strap.

Other objects and advantages of my invention will more fully appear from the following detailed description taken in connection with the accompanying drawing which illustrates a single embodiment thereof and 75 in which:

Figure 1 is an elevation of a shipper of my invention partly broken away in order to show the position of an ice-cream can therein;

Figure 2 is an enlarged vertical sectional view through the shipper shown in Figure 1;

Figure 3 is a plan view of the shipper showing the cover in its open position, and

Figure 4 is a plan view of the shipper with the cover applied and secured to the container.

In the drawings like reference characters designate similar parts throughout the several views.

The shipper comprises two parts, namely a container 10 and a cover or top therefor 11. Each of these parts comprises a single molded member which may be made in any suitable rubber molding apparatus. Of course, it is to be understood that although I have disclosed the shipper as being preferably made of rubber, the invention is not to be thus limited for obviously there are a number

of other plastic materials which might be used in place of rubber.

The container 10 includes a base 12 and a cylindrical wall 13 formed integral therewith. The upper edge of the wall 13 has formed on its outer side an annular rib 14 defining a shoulder 15 for receiving a ring-like flange 16 formed integral with the top 11. Attention is directed to the fact that the top 11 includes an irregularly formed portion 17 disposed integral with the flange 16 and shaped to conform with the top of an ice-cream container. In fact, both the container and the top are so shaped as to receive and conform to the shape of the ice-cream can.

The interior surface of the wall 13 has formed integral with it a plurality of spaced vertical ribs 18 adapted to embrace the wall of the can inserted in the container. Also it is to be noted that the portion 17 of the top 11 has formed in it a plurality of slanting spaced ribs 19 adapted to engage the top of an ice-cream can such as the can shown in Figure 1 and designated generally by the reference character 20.

Attention is directed to the fact that even though the wall of the ice-cream can may have slight bumps or other irregularities 30 therein, these irregularities will not prevent the insertion of the can in my rubber shipper due to the fact that the wall 13 of the shipper is relatively flexible and can readily conform to the shape of the can therein. Of course, 35 it is to be remembered that even though the wall 13 is flexible, the container as a whole is relatively rigid, so that it is at all times maintained in substantially the shape shown in Figure 1.

40 The ribs 18 and 19 serve to space the wall and top of the can in the shipper from the inner surfaces of the container 10 and the top 11, so that air pockets are maintained between the shipper and the outer surface 45 of the can. These air pockets will aid in the preservation of the ice-cream or other perishable goods in the can within the shipper.

The top 11 of the shipper is secured to the container 10 by means of a rubber strap 21 50 having an intermediate portion thereof formed into a handle portion 22. One end of the strap has connected to it a hinge 22 which is fastened to the rib 14 of container 10 and flange 16 of top 11 and serves to hingeably 55 connect the top to the container. The other end of the strap 21 has apertures formed therein so as to cooperate with a buckle 23 secured at 24 to the wall 13 of container 10. It will be evident that when the free end of 60 the strap is in cooperation with the buckle 23, the handle 22 may be used to lift the shipper.

65 My novel shipper is highly advantageous in view of the fact that it may be readily sterilized and may be roughly handled with-

out damaging the ice-cream can therein, since the rubber of which the shipper is made takes up any impact or blow which may be imposed upon the shipper during the handling of the same. Also it is to be noted that the cover 70 11 has a tight fit on top of the container 10, so that when the cover is in its closed position the inside of the shipper is completely sealed from the surrounding atmosphere thus enabling the ice-cream or other perishable goods therein to be insulated from the deleterious effects of the atmosphere.

Now, of course, it is to be understood that although I have illustrated and described in detail the preferred form of my invention, the invention is not to be thus limited, but only in so far as defined by the scope and spirit of the appended claims.

I claim as my invention:

1. A shipper for cans of perishable goods, such for example as ice-cream, comprising a relatively rigid container formed to receive and conform with the shape of the can and comprising a molded plastic construction, the wall of which is relatively flexible so as to enable the shipper to conform to any irregularities such as bumps in the wall of the can and the ends of which are shaped to tightly cooperate with the ends of the can.

2. A shipper for cans of perishable goods, such as ice-cream, comprising a molded rubber construction including a container proper and a top therefor, and a strap for anchoring the top to the container proper, said strap being formed to serve as a handle.

3. A shipper for cans of perishable goods, such as ice-cream, comprising a molded rubber construction including a container proper and a top therefor, and a strap for anchoring the top to the container proper, said strap being formed to serve as a handle and having one of its ends connected to a hinge serving to hingeably connect the top to the container proper and having its other end arranged for cooperation with a buckle carried by the container.

4. In a shipper for cans of perishable goods, such for example as ice-cream, a molded plastic construction shaped to conform with the outer configuration of the can and comprising a container proper and a top cooperable therewith, said top having a depending flange for cooperation with the upper end of the container, and said container proper being relatively rigid and having a relatively flexible wall terminating at its upper end in a portion shaped to tightly receive and accommodate the flange formed on the cover.

5. In combination, a can of perishable goods to be shipped, and a shipper for receiving said can and formed to conform with the shape of the can, said shipper comprising a container proper for receiving the major part of the can and a top designed for tight

cooperation with the container and shaped to conform with the top of the can, said container proper and top of the shipper having a plurality of protuberances formed in each of their internal surfaces for spacing the can from the inner surface of the wall of the container and the top, thus forming air pockets between the shipper and can.

6. In combination, a can of perishable goods to be shipped, and a shipper for receiving said can and formed to conform with the shape of the can, said shipper comprising a container proper for receiving the major part of the can and a top designed for tight cooperation with the container and shaped to conform with the top of the can, said top being connected and held on the container by a strap formed to serve as a handle, said strap extending transversely over the upper surface of the top of the shipper.

In testimony whereof I have hereunto subscribed my name at Eau Claire, Eau Claire County, Wisconsin.

SPENCER O. STAAKE.
